MEANS FOR OPERATING ELECTRIC EDDY CURRENT FURNACES

Ludwig Dreyfus, Västerås, Sweden, assignor to
 Allmänna Svenska Elektriska Aktiebolaget,
 Västerås, Sweden, a corporation of Sweden

Application November 26, 1935, Serial No. 51,589
 In Sweden September 20, 1934

7 Claims. (CL 13—26)

I have filed an application in Sweden September 20th, 1934.

This invention relates to installations of electric eddy current furnaces.

5 It has been heretofore proposed to provide such installations in which the winding is divided into several sections connected in series and it has also been proposed to divide the current source feeding the said winding into several sections connected between the sections of the furnace winding, and condensers for compensating the reactance of the furnace winding sections are connected with the latter in parallel or in series.

10 15 It is found in practice that the said reactance is strongly variable, not only during the same melting process, depending on the difference in the electric and magnetic properties of the solid and the molten metal, but also for different melting processes, depending on the different degree of filling of the furnace. It is always desirable that the compensation of the reactance be as accurate as possible, and this necessitates an adjustment of the capacity of the condensers.

20 25 It has now been found that, for an alternating series connection of sections of the current source and of the furnace winding, the said adjustment can be essentially simplified if the condensers, instead of being connected in series or in parallel to the furnace winding sections, are connected between the terminals of the current source sections. Such a connection forms the object of the present invention. An examination shows that by such a connection all the condensers belonging to a number of series connected furnace winding sections can be adjusted in common for being adapted to the total reactance, of the winding sections, said total reactance as a rule, being not subjected to proportional variations so large as the separate partial reactances. This is the case particularly if the different winding sections are situated at different height because the reactance then increases for an upper section at the same time

30 35 40 45 as it decreases for a lower one by reason of the flowing-down of the molten metal from the former section to the latter.

The reason for connecting sections of the furnace winding alternatingly in series with sections of the current source may be not only the necessity or desirability of lowering the maximum voltage to ground of the furnace winding but also the desire to pass through the winding two different species of current and to reduce the mutual action of these on each other to the small-

est possible. For instance, the same winding may be simultaneously fed by singlephase high frequency current for the heating and by two- or polyphase low frequency current for stirring the molten charge. The sections which are connected in series for the high frequency current may then for instance belong to different phases of the low frequency system.

5 10 15 Three forms of the invention arranged in the last-mentioned way are diagrammatically shown in the accompanying drawing in Figs. 1-3. For simplifying the different diagrams of connection, different parts of such windings which generally are mounted on the same machine, are placed in the diagram distant from each other and close to the portions of the furnace winding with which they cooperate most closely.

20 25 30 35 In Fig. 1, the furnace winding is connected in twophase for the low frequency stirring current and is for this purpose divided into four sections or coils U_1 , U_2 , U_3 , U_4 , which are supposed to be mounted above each other in the order mentioned, for instance with U_1 at the top. For the high frequency current, the coils are series-connected in pairs, U_1 being connected in series with U_4 , and U_2 being connected in series with U_3 . In operating the furnace, the top coil will frequently obtain the highest reactance and the bottom coil the lowest reactance, because the former may often be practically without any secondary circuit (when the furnace is not completely filled), while the latter is very soon filled with a completely molten charge, which therefore reaches the wall of the furnace crucible. By connecting together the coils in this way, there will therefore be the greatest probability for substantially equal reactance in both circuits.

40 45 50 55 Within each of the high frequency circuits thus formed, the furnace coils are, as already mentioned, connected in series alternating with the sections of the generator winding, and the condensers for compensating the reactance of the furnace coils are, according to the invention, connected in parallel to the said generator winding sections. Those of the latter sections which feed the circuit containing U_1 and U_4 , are designated by H_1 and H_4 and those belonging to the other circuit by H_2 and H_3 . The generator windings are series-connected with condensers for compensating their inherent reactances, said condensers being individual for the generators H_2 and H_4 and designated by S_2 and S_4 , but for the windings H_1 and H_3 combined into a common condenser S_{13} . It is also possible to combine the windings H_1 and H_3 into one. In this manner,

each combination of a winding and a series condenser will at its terminals thus give a practically constant voltage independent of the load. In parallel to each such combination, there is 5 connected a condenser, C_1 , C_2 , C_3 , C_4 respectively, for compensating the reactances of the furnace windings. Finally, a pair of windings L_{13} and L_{24} of a low frequency twophase generator are so connected that the former winding will feed the 10 coils U_1 and U_3 in series while the latter feeds the coils U_4 and U_2 in series. If the windings are so wound that the high frequency ampere turns will reinforce the fluxes of each other, the low frequency ampere turns will then counteract each 15 other in the axial direction, but instead of that cooperate in such a manner as to form a substantially radial flux wandering in a vertical direction, said flux producing, in cooperation with the eddy currents induced thereby in the furnace charge, vertical tangential forces for stirring the charge. This different action of the high 20 frequency and of the low frequency ampere turns is indicated in the figure by full-drawn arrows for the former ones and dotted arrows for the latter ones. The same arrows also represent the 25 directions of current in the coils so as to make it possible to check the course of the different currents. The condensers form bars to the low frequency currents, and the windings of the low frequency generator bar the high frequency currents when the distribution of inductance is uneven, while on the other hand no such barring is necessary when the inductance distribution is even, because the points connected through the 30 low frequency windings are then equipotential points for the high frequency current.

Figs. 2 and 3 show two different examples of the connection for a threephase arrangement of the low frequency circuits. In both cases, the 40 furnace winding and the windings of the high frequency and low frequency generators are divided into six sections or coils each. In Fig. 2, the furnace coils are connected in pairs alternately with the main condensers so as to form 45 three circuits. The first circuit, for instance, contains the top coil U_1 and the bottom coil U_6 of the furnace and the corresponding condensers C_1 and C_6 in parallel to the high frequency generator windings H_1 and H_6 with their 50 series condensers S_1 and S_6 . The second circuit contains the furnace coils U_5 and U_4 and the condensers C_5 and C_4 and the high frequency generator windings H_5 and H_4 with their series condensers S_5 and S_4 . The third circuit contains 55 the furnace coils U_3 and U_2 , the condensers C_3 and C_2 and the high frequency generator windings H_3 and H_2 with their series condensers S_3 and S_2 . Between the angles of the three high frequency circuits, the windings L_1 — L_6 of the low 60 frequency generator are connected in such a manner that a current phase generated by L_1 and L_4 for example will pass through the furnace windings U_1 and U_4 in opposite directions represented by the dotted arrows. Also in this 65 case the low frequency currents will thus produce, in coils arranged above each other, a substantially radial flux moving in a vertical direction so as to impart a corresponding movement to the furnace bath.

In Fig. 3, the furnace coils U_1 — U_6 and the high frequency generator windings H_1 — H_6 form 70 two closed circuits, each containing three coils of each kind. One of the circuits contains the coils having odd numbers and the other the 75 coils having even numbers. Otherwise the con-

nection is analogous to that of Fig. 2, the windings of the low frequency generator being connected in pairs between the junction points of the two closed circuits. The windings, condensers and directions of current are also designated in 5 the same manner as in Fig. 2, and the operation will be exactly analogous to that of the said figure.

I claim as my invention:

1. In electric eddy current furnace installations, a furnace winding divided into sections, a high frequency current source divided into sections each connected in series with one of said furnace winding sections, and condensers for compensating the reactance of said furnace winding connected between the terminals of said current source sections. 10

2. In electric eddy current furnace installations, a furnace winding divided into sections combined into independently fed groups, a high frequency current source for feeding said furnace winding divided in a corresponding manner into groups of sections, the individual current source sections in each group being each separately connected in series with a different individual section of the furnace winding in each group, and condensers 15 for compensating the reactance of said furnace winding connected between the terminals of said current source sections. 20

3. In electric eddy current furnace installations, a crucible, a winding surrounding said crucible and divided into sections arranged one above the other, a high frequency current source divided into sections individually connected in series with said furnace winding sections, and condensers 30 for compensating the reactance of said furnace winding connected between the terminals of said current source sections. 35

4. In electric eddy current furnace installations, a crucible, a winding surrounding said crucible and divided into sections which are arranged one above the other and combined into independently fed groups, sections mounted at considerable distance from each other being combined into one group, a high frequency current source for feeding said furnace winding divided in a corresponding manner into groups of sections, the current source sections in each group being connected alternately in series with the furnace winding sections in each group, and condensers for compensating the reactance of said furnace winding 45 connected between the terminals of said current source sections. 50

5. In eddy current furnace installations, a furnace winding divided into sections, a high frequency current source divided into sections connected alternately in series with said furnace winding sections, condensers for compensating the reactance of said furnace winding connected between the terminals of said current source sections, and a two- or polyphase low frequency 55 current source connected to feed each phase of current through at least two furnace winding sections, half of the number of these in opposite direction to the others, compared with the direction of the high frequency current. 65

6. In electric eddy current furnace installations, a furnace winding divided into sections combined into independently fed groups, a high frequency current source for feeding said furnace winding divided in a corresponding manner into groups 70 of sections, the current source sections in each group being connected alternately in series with the furnace winding sections in each group, condensers for compensating the reactance of said furnace winding connected between the terminals 75

of said current source sections, and a multiphase low frequency current source connected to feed each phase of current through at least two furnace winding sections belonging to different groups.

7. In electric eddy current furnace installations, a furnace winding divided into sections combined into independently fed groups, a high frequency current source for feeding said furnace winding divided in a corresponding manner into groups of sections, the current source sections in each

group being connected alternatingly in series with the furnace winding sections in each group, condensers for compensating the reactance of said furnace winding connected between the terminals of said current source sections, and a multiphase low frequency current source having each phase divided into several series-connected portions which are connected between different points of said groups of the furnace winding and of the high frequency current source. 10
